RAINCOAT

Ann M. Cetrulo, Park Hills, Ky.

Application November 1, 1956, Serial No. 43,632

Term of patent 14 years

(Cl. D3—5)

FIG. 1.

FIG. 3.

FIG. 2.

FIG. 4.

The raincoat is shown upon the dotted figure of a wearer for convenience of illustration.

I claim:

The ornamental design for a raincoat, substantially as shown and described.
